CLAIM

The ornamental design for a dog barking restraining device, as shown and described.

DESCRIPTION

FIG. 1 is a front, right and top perspective view of a dog barking restraining device, showing our new design; FIG. 2 is a rear, left and bottom perspective view thereof; FIG. 3 is a front view thereof; FIG. 4 is a rear view thereof; FIG. 5 is a left side view thereof; FIG. 6 is a right side view thereof; FIG. 7 is a top plan view thereof; FIG. 8 is a bottom plan view thereof; FIG. 9 is an enlarged view of portion 9 shown in FIG. 1; and, FIG. 10 is a rear, perspective exploded view thereof. The broken lines shown in the drawings illustrate portions of the dog barking restraining device that form no part of the claimed design.

(Continued)

The dash-dot-dash lines in FIGS. 1 and 9 are annotative for indicating the bounds and magnified area of the portions of the device shown in enlargement, and form no part of the design claim.
